UNITED STATES PATENT OFFICE.

FRANK H. WEIMER, OF NOGALES, ARIZONA.

AIR-VALVE FOR FLUID-PRESSURE BRAKE SYSTEMS.

1,284,000.

Specification of Letters Patent. Patented Nov. 5, 1918.

Application filed January 22, 1917. Serial No. 143,622.

To all whom it may concern:

Be it known that I, FRANK H. WEIMER, a citizen of the United States, residing at Nogales, in the county of Santa Cruz and State of Arizona, have invented certain new and useful Improvements in Air-Valves for Fluid-Pressure Brake Systems, of which the following is a specification.

My invention relates to improvements in air-valves for fluid-pressure brake systems, and more particularly to combine automatic and straight air valves such as are usually operated by compressed air and designed for use on railroad cars and locomotives and either operated automatically by the reduction of air in the train brake pipe pressure and using the auxiliary reservoir air pressure in the well-known manner, or by increasing the normal train brake-pipe pressure and using straight air from the main reservoir of the locomotive direct to the brake-cylinder.

The object of my invention is to provide a positive acting automatic and straight air valve for setting brakes, with straight air or automatically, by increasing or reducing the normal train-pipe air-pressure through the medium of the engineer's valve.

A further object is to provide an improved valve of the class or type above described, whereby the brake may be applied, held, and released at the will of the engineer, applying the brakes by the use of straight air and at the same time applying them automatically in the event of a break in the train pipe or hose.

A further object of my invention is to provide a valve which is simple, inexpensive, and durable in construction and easy and effective in operation.

My invention consists in the several features and in the construction, combination, and arrangement of the features as more fully hereinafter described and claimed.

Referring to the drawings, Figure 1 is a central longitudinal section, showing the several parts of the valve in the relative positions they assume when the air is released; Fig. 2, a central longitudinal section, showing the several parts of the valve in the relative positions they assume when straight air is being used; Fig. 3, a central longitudinal section, showing the several parts of the valve in the relative positions they assume when the valve is in the position known as the "holding" position; Fig. 4, a central

longitudinal section, showing the several parts of the valve in the relative positions they assume when automatically operated in the event that a break occurs in the train pipe or hose; Fig. 5, a cross-section on the line 5 5 of Fig. 1, showing particularly the straight air and exhaust or relief parts; Fig. 6, a cross-section on the line 6 6 Fig. 2; Fig. 7, a side elevation of the slide valve; Fig. 8, a bottom plan view of the slide valve; Fig. 9, a top plan view of the slide valve; Fig. 10, a cross-section of the valve; Fig. 11, an end view of the piston-rod; Fig. 12, an end view of the flange-cap; and Fig. 13, a bottom plan view of the slide valve in a retarded released position.

In the drawings, in which similar reference characters denote corresponding parts throughout the several views, 1 represents the inclosing casing of the valve, made preferably in two hollow parts, 2 and 3, secured together by means of bolts 4 and provided with a screw-cap 5 at one end and a screw-plug 6 at the other end, having a plurality of air-holes or apertures 7 leading to the auxiliary reservoir.

The hollow part 3 of the casing is provided with a strong spiral spring 8, seated at its inner end in a slideable cap 9, and its outer end abutting against a screw-plug 10, which is adapted to be adjusted in order to regulate the tension or strength of the spiral spring 8.

The hollow part 2 of the casing is provided with a flanged cap 11 at its outer end, which is provided with a plurality of air holes or apertures 12, normally seated against a shoulder 13 of the part 2 and held against the shoulder by means of a spiral spring 14.

At the upper portion of the part 2 an angular by-pass or passage 15 is provided and at the lower portion is provided an angular by-pass or passage 16, partly formed in the parts 2 and 3.

An air-chamber 17 is provided in the lower portion of the part 2, which receives compressed air from the train-pipe (not shown), and chamber 18, in which the piston-head to be hereinafter described operates.

A horizontal passage 19, for the passage of compressed air to and from the brake-cylinder, is provided in the lower portion of part 2, and 20 is a vertical port communicating with the passage 19, which is pro-

vided with a plug-valve 21 for closing the port 20 when desired. An exhaust-port 20^a is provided in the part 2, which is open to the outer air.

5 A piston 22 is provided which comprises a head 23, slidably mounted in chamber 18, and a piston-rod 24, slidably mounted in a chamber 25 of the part 2 of the casing, having one end 26 enlarged or flanged and 10 provided with a plurality of air holes or apertures 27.

A slide-valve 28 is provided, having a vertical wedge-shaped portion 29, which is seated in a wedge-shaped elongated opening 30 of the valve-stem and is provided with a leaf spring 31 at the top, which bears resiliently against the upper surface of the chamber 25 and retains the valve seated in close and intimate contact with the lower 20 surface of the chamber 25 and produces a liquid-tight joint.

The slide-valve 28 is provided with a port 32, adapted to register with the port 20 when straight air is used, (see Fig. 2,) a 25 central cavity 33, adapted to register with the port 20 and exhaust port 20^a, (see Fig. 1,) and a port 34, adapted to register with the port 20 automatically and open communication between the auxiliary reservoir (not 30 shown) which is secured at the right-hand end of the part 2 of the inclosing casing.

The operation is as follows: When the normal train-pipe pressure is increased, through the instrumentality of the engineer's valve, to set the brakes, air passes from the train-pipe through chamber 17 and by-pass 16 to cylinder 18, pushing piston 24 and uncovering groove 15, allowing air to pass around the piston-head freely, and 40 a part of the volume of air passes through air-holes 27, 12 and 7 to the auxiliary reservoir at the left. When piston 23 is moved ahead, uncovering groove 15, slide-valve 28 is also moved ahead, connecting passage 32 45 in the slide-valve 28 with passage 20 in casing 1, Fig. 2, thereby opening up free passage for air from the train-pipe through the passage 19 to the brake-cylinder. When the engineer has sufficient pressure on the brakes, 50 and wishes to hold them, he reduces the train-pipe pressure, through the instrumentality of the engineer's valve, when equalization takes place, the spring 14 forcing slide-valve 28 back far enough to break connections between passages 32 and 20, but not 55 far enough to permit the groove 33 to connect passage 20 with exhaust 20^a, thereby holding air in the brake-cylinder and auxiliary reservoir (see Fig. 3). When the engineer desires to release the brakes, he reduces the train-pipe pressure and the piston 22 and slide-valve 28 are moved back to release position, as shown in Fig. 1, but will not pass release with any ordinary reduction 60 of the train-pipe pressure, as spring 8 is 65

adjusted by screw-plug 10 to resist all train-pipe reductions which are a little less than emergency applications. To operate the automatic side of the valve, the engineer reduces the train-pipe pressure sufficiently to 70 overcome spring 8, when the piston valve will move back and connect passage 34 in slide-valve with passage 20 in casing, thereby opening communication between the auxiliary reservoir and brake-cylinder, and the 75 air will be held in the brake cylinder. To release the brakes in an automatic application, the engineer increases the train-pipe pressure when the slide-valve will move ahead past the release position, when a slight reduction will move the slide-valve 80 back to release. It is evident that it is better to use straight air in all cases of ordinary applications of the brakes, the automatic air to be conserved in reservoirs to be 85 applied in the event of an accident to the train pipe or hose.

It is obvious that a slight reduction of the train-pipe air pressure when the valve is in straight air lap position will cause the piston 90 22 and slide-valve 28 to move back to release position on the front cars, where the force of the reduction is greatest. Spring 8 will yield a little and allow cavity 33 to partly 95 overlap or choke passages 20 and 20^a, Fig. 13, resulting in a restricted release; but at the rear cars, where the reduction is less, slide-valve 28 will be stopped at normal release.

I do not wish to be understood as limiting myself to the specific details of construction 100 as shown and described, as the same may be modified without departing from the spirit and scope of my invention.

Having thus described my invention, what I claim is:—

1. In an air-brake system, a casing having 105 a chamber with vertical ports and a slideable spring-controlled flanged cap projecting within said chamber, a piston also mounted in said chamber having an end adapted to contact with and to slide said flanged cap, a slide-valve mounted in said piston chamber having a laterally-extending port in its under surface and two vertical ports adapted to register and communicate with the vertical ports of the casing.

2. In an air-brake system, a casing having 110 a chamber with ports, a piston mounted in said chamber provided with a valve having two circular ports extending entirely therethrough, one being substantially vertical and the other curved, and a single elongated curved port formed in the under surface thereof, said circular ports each adapted to register and communicate with one of the 115 ports of the said chamber, and the single upwardly curved port adapted to simultaneously register with both of the ports of the said chamber, said piston and valve being subject to the variations in the train-pipe 120

125 130

air-pressure and adapted to release air on the reduction of the air-pressure in the train-pipe and a restricted exhaust on a further reduction of the air-pressure in the train-pipe.

3. In an air-brake system, a casing having outer-air and brake-cylinder ports, one substantially vertical and the other curved, by-pass ports, communicating chambers, a piston having a head mounted in one of said chambers which regulates the opening and closing of one of the by-pass ports, and a stem mounted in the other chamber, a valve mounted in said piston-stem and provided with ports which register and communicate only with the outer air and brake-cylinder ports of the casing.

4. In an air-brake system, a casing having a chamber with substantially vertical ports, a piston mounted in said chamber provided with a slide-valve having at one side thereof two substantially vertical circular ports ex-

tending entirely through said valve and a single laterally-extending elongated port formed in the under surface of said valve, 25 said annular ports adapted to communicate with the two vertical ports of the chamber and said single elongated port adapted to register and communicate simultaneously with both of the substantially vertical ports 30 of the said chamber, said piston and valve being subject to the variations in the train-pipe air pressure and adapted to release air on the reduction of air-pressure in the train-pipe and a restricted exhaust on a further reduction of the air-pressure of the train-pipe.

In testimony whereof I affix my signature in the presence of two witnesses.

FRANK H. WEIMER.
